UNITED STATES PATENT OFFICE.

ALFRED WILLIAM BENNIS, OF BOLTON, ENGLAND.

WATER-HEATING AND STEAM-GENERATING BOILER.

Application filed August 3, 1925, Serial No. 47,930, and in England August 1, 1924.

The present invention relates to improvements in boilers and the like plant for the raising of steam and more particularly those adapted for use with liquid, gaseous atomized, or powdered fuel.

According to the present invention the whole or a considerable proportion of the effective heating surface of the boiler is arranged to be below or substantially below 10 the main combustion chamber.

In such an arrangement the gases of combustion may be passed downwards through the tubes in single pass or multiple pass manner, that is to say for instance, they 15 may pass down through one section of a bank or banks of steam generating tubes and then up through another section of said tubes, the said tubes being preferably inclined to ensure proper circulation.

20 The invention is more particularly described with reference to the accompanying drawings, in which:

Figure 1 is a sectional side elevation through one form of construction.

25 Figure 2 is a corresponding view of a modified form of construction.

Figure 3 shows a sectional side elevation of a third form of construction.

30 Figure 4 is a similar view showing the arrangement of the present invention applied to a two pass boiler.

Figure 5 is a view of an arrangement of the present invention applied to a two pass boiler with additional heating tubes to those 35 shown in Figure 4, and the consequential arrangement of these tubes.

Figure 6 is a sectional elevation of Figure 5.

40 The gases of combustion from a burner or burners 1 mounted at the top of the combustion chamber 2 which may be adapted for the burning of powdered liquid or gaseous fuel, pass down through boiler tubes 3, 4, which form the whole or the major portion 45 of the water heating surface of the boiler. The gases may then pass upwards or radially outwards and into a flue 5 which may contain an air heater or economizer. The usual super-heating tubes 6 can be pro-

50 vided between the first and second groups of boiler tubes 3, 4. These boiler tubes are connected at their ends to headers 7, as shown, or to water legs or drums. These headers are connected to the steam drums 8, 8^a, by

55 ably forming a water cooling surface for the walls for the furnace.

In the arrangement shown, the water will pass down from the steam drum 8 by means of the pipes 10, and through the groups of 60 tubes 3, 4, whereupon the heated water passes upwards to the steam drums 8, 8^a, through the tubes 9.

The floor 11 receiving the ash or the like solid residue of combustion is preferably 65 water cooled by the provision of a series of tubes 12 lying in spaced relationship along it and connected to a water header 13 at one end, and to a mud drum 14 at the other end, which mud drum 14 is connected to the 70 headers 7 on one side of the boiler by means of a pipe 15, whilst the water header 13 is connected to water headers 7 at the other side of the boiler by means of a pipe 15^a, thus providing a water cooling surface for 75 the floor 11 of the furnace. Whilst these tubes are shown laid upon the brickwork floor, they may be arranged in open grooves or closed passages within this floor, if desired.

80 In the modified arrangement shown in Figure 2 the ash and the like solid residue from the combustion falls into hoppers 16 which may be provided with discharge devices. This figure shows, by way of example, the application of a water screen 17 arranged above the floor of the ash hopper. The gases of combustion in this case will, therefore, pass through the first bank of tubes 18, then over the superheater tubes 90 19, then over a second bank of tubes 20, then over the tubes 17 forming the water screen, and then outwards through the flue 38 upwards and out through the flue 39 which may include an economizer, air heater 95 or both such elements.

90 In the boiler arrangement shown in Figure 3, the first and second main groups of tubes of the boiler 21, 22 respectively, are inclined in different directions to one another, the steam drum 23 being itself below the level of the burners 1, so that the whole of the boiler lies below the burners 1 and the combustion chamber 2.

100 In this arrangement the furnace is shown 105 by way of example to have a floor which itself forms an ash or the like refuse collecting hopper 23, which may be provided with any known form of discharge device, such as 24. The floor of this hopper may simi- 110

larly be protected by means of a series of water tubes 25 which form part of the water circulating system of the boiler.

Also in this case it will be seen that the gases of combustion from the combustion chamber 2 pass through the main tubes of the boiler in a downward direction, and thence outwards and upwards, whence they pass into the exit flue 26 which may contain 10 an air heater, economizer or the like.

The arrangement of the present invention is also applicable to multiple pass boilers, as shown in Figure 4, where the gases of combustion pass through the water tube groups 15 27, 28, forming the boiler in double pass, these tubes being divided into two passes by a partition wall 29.

The combustion chamber 2 and the outlet flue 30 are separated by suspended walls 31, 20 32, which preferably have an air space 33 between them, and are supported in such a manner that the tubes 27 are not called upon to bear any portion of the weight of such walls.

25 If desired, the space 33 between the walls 31, 32 may be closed and air circulated through this space, which can, therefore, be used as a pre-heating means for the air to be used for the purpose of combustion.

30 In addition to the super-heater or super-heater units shown in the drawings, an interstage re-heater may be used within a suitable location and in appropriate location to the main steam generating tubes of the 35 boiler, such re-heater supplying heat energy to the steam discharged from the high pressure section of a steam turbine or engine and delivered to the low pressure section of such steam turbine or engine after again being 40 subject to the heat of combustion in the furnace.

A prime advantage of the present invention is that the evaporative efficiency of the heating surface when placed below the combustion chamber is materially greater, per 45 unit of surface, than when placed in the ordinary manner above or substantially above or at the side of the combustion chamber, as has hitherto been the practice, this effect being especially the case when, according to 50 my invention, the flame and gases of combustion are caused to pass directly through the steam generating tubes in one or more passes.

55 In addition to the main boiler tubes additional heating tubes 34 in suitable connection with headers or drums 35, can be provided, either upon or spaced slightly away from, the enclosing walls of the furnace, and these may be provided with fins or ribs of steel or iron welded to or formed integral with them to increase the effective heating 60 surface of these tubes. An economizer may be advantageously placed at 30 in the construction according to Figure 5.

I declare that what I claim is:

1. A water heating and steam generating boiler comprising a combustion chamber, a heating chamber below said combustion chamber in open communication therewith, 70 banks of substantially horizontal boiler tubes situated within said heating chamber and forming part of the effective heating surface of the boiler system, vertical headers to which the banks of tubes are connected at their ends, steam drums connected to the vertical headers, fuel jets in the roof of the combustion chamber for projecting the gases of combustion downwardly through said banks of boiler tubes, and a water cooled floor for said combustion chamber adapted to receive the solid residue or ash 75 from the products of combustion.

2. A water heating and steam generating boiler comprising a combustion chamber, a heating chamber below said combustion chamber in open communication therewith, 80 banks of substantially horizontal boiler tubes situated within said heating chamber and forming part of the effective heating surface of the boiler system, vertical headers to which the banks of tubes are connected at their ends, steam drums connected to the vertical headers, fuel jets in the roof of the combustion chamber for projecting the gases of combustion downwardly through 85 said banks of boiler tubes, and a water cooled floor for said combustion chamber in the form of a collecting hopper adapted to receive the solid residue or ash from the products of combustion.

90 3. A water heating and steam generating boiler comprising a combustion chamber, a heating chamber below said combustion chamber in open communication therewith, 95 banks of substantially horizontal boiler tubes situated within said heating chamber and forming part of the effective heating surface of the boiler system, vertical headers to which the banks of tubes are connected at their ends, steam drums connected to the vertical headers, fuel jets in the roof of the combustion chamber for projecting the gases of combustion downwardly through 100 said banks of boiler tubes, and a water cooled floor for said combustion chamber in the form of a collecting hopper adapted to receive the solid residue or ash from the products of combustion.

105 3. A water heating and steam generating boiler comprising a combustion chamber, a heating chamber below said combustion chamber in open communication therewith, 110 banks of substantially horizontal boiler tubes situated within said heating chamber and forming part of the effective heating surface of the boiler system, vertical headers to which the banks of tubes are connected at their ends, steam drums connected to the vertical headers, fuel jets in the roof of the combustion chamber for projecting the gases of combustion downwardly through 115 said banks of boiler tubes, a passage for the upward flow of the gases after their flow through the said banks of boiler tubes, a combustion air preheating device comprising a hollow suspended wall separating such passage from the combustion chamber, and a water cooled floor for said combustion chamber adapted to receive the solid residue or ash from the products of combustion.

120 4. A water heating and steam generating boiler comprising a combustion chamber, a heating chamber below said combustion chamber in open communication therewith, 125 banks of substantially horizontal boiler tubes situated within said heating chamber and forming part of the effective heating

surface of the boiler system, vertical headers to which the banks of tubes are connected at their ends, steam drums connected to the vertical headers, fuel jets in the roof of the combustion chamber for projecting the gases of combustion downwardly through said banks of boiler tubes, a passage for the upward flow of the gases after their flow through the said bank of boiler tubes, a hollow suspended wall separating such passage from the combustion chamber, means to circulate air through the said hollow wall to be heated and then used for the purpose of combustion, and a water cooled floor for said combustion chamber adapted to receive the solid residue or ash from the products of combustion. 5. A water heating and steam generating boiler comprising a combustion chamber, a heating chamber below said combustion chamber in open communication therewith, banks of substantially horizontal boiler tubes situated within said heating chamber and forming part of the effective heating surface of the boiler system, vertical headers to which the banks of tubes are connected at their ends, steam drums connected to the vertical headers, fuel jets in the roof of the combustion chamber for projecting the gases of combustion downwardly through said banks of boiler tubes, water drums spaced below the heating chamber, water screens connecting the steam and water drums and protecting the furnace walls, and a water cooled floor for said combustion chamber adapted to receive the solid residue or ash from the products of combustion. 25 30 35

In witness whereof, I have hereunto signed by name this 22nd day of July 1925.

ALFRED WILLIAM BENNIS.
